UNITED STATES PATENT OFFICE.

DAVID F. GEIGER, OF SASKATOON, SASKATCHEWAN, CANADA.

ACETYLENE-GAS GENERATOR.

1,264,057.

Specification of Letters Patent. Patented Apr. 23, 1918.

Application filed July 10, 1916. Serial No. 108,259.

To all whom it may concern:

Be it known that I, DAVID F. GEIGER, a citizen of the United States, residing at Saskatoon, in the Province of Saskatchewan, 5 Dominion of Canada, have invented a new and useful Improvement in Acetylene-Gas Generators, of which the following is a specification:

This invention relates to certain new and 10 useful improvements in acetylene generators, wherein simplicity in design is combined with a high degree of efficiency to produce a gas generator in which the gas producing agent, such as calcium carbid, is fed 15 automatically into a body of water to liberate gas and to maintain the same under a constant and even pressure so as to avoid sputtering and fluctuation.

Another object of the invention is to provide 20 a device of this type whereby danger of explosion caused by a "flash-back" is reduced to a minimum.

A further object is the provision of improved means for feeding the carbid into 25 the water; of such means for regulating the pressure of gas; for controlling the constant and even pressure of gas during the recharging of the apparatus with carbid; and for removing the residue from the bottom of the 30 generator.

Other and further objects and advantages of the invention will be hereinafter set forth and the novel features thereof defined in the appended claims.

35 In the drawings

Figure 1 is a sectional elevation, partly broken away, of my improved device; Fig. 2 is a section of a detail of the lower portion of the tank; Fig. 3 is a section taken on the 40 line X—X of Fig. 1; Fig. 4 is a side view partly broken away and in section of the water wheel motor; and Fig. 5 is a partial detail of the peripheral construction of such wheel motor.

45 Like numerals of reference refer to like parts in the several figures of the drawings.

Referring to the drawings, A represents a pressure tank of any suitable configuration and material, though preferably, as 50 shown, cylindrical in shape and of metal to best accomplish the objects for which it is designed, the tank being provided at its lower extremity with legs or standards 10 so as to space it above the ground or other 55 support upon which it may be set up.

Secured in any desired manner about the

inner periphery of the upper open end of the tank, is a cone-shaped hopper 11 adapted to be filled through a suitable plug 12 threaded into a centrally disposed aperture 60 13 formed in a closure member 14 fastened by bolts 15, or other means, over the open end of the tank and to the edges thereof as shown. A plurality of rods 16, having threaded engagement with the hopper, extend 65 downwardly therefrom and support at their lower ends a plate 17, from which depends an auxiliary pressure tank B, the purpose of which will hereinafter appear, a boss or protuberance 18 integrally attached 70 to the tank B extending through the central point of the plate and affording means for securing the tank thereto.

A suitable distance below the frustum or delivery end of the hopper 11 is a receiving 75 and feeding disk 19 mounted upon a bevel gear 20, the gear being provided with a step bearing 22 formed in the adjacent portion of the protuberance 18.

A bracket 24 is secured at one end about 80 the boss 18 upon the plate 17, as by means of a nut 25, and has its other end bifurcated to form a journal bearing 26 for a shaft 27 carrying at its inner end a bevel pinion 28 engaging the gear 20 and extending outwardly through a suitable stuffing box 29 mounted on the wall of the tank A, a notched hand wheel 30 being secured to the free end of the shaft as shown in Fig. 1. Keyed or otherwise secured upon this shaft intermediate the bushing and journal is a pocketed 90 wheel motor C, the particular description and objects of which will subsequently appear.

Tapped into a wall of the tank A is a 95 water channel 31 having a shut off valve 32 and a check valve 33 therein and terminating at its outer end in a T-coupling 34 to the upper end of which is connected a joint 35 through the medium of a short threaded 100 pipe 36, said joint being enlarged and internally threaded to receive the exteriorly threaded reduced end 37 of the lower section 38 of a two-piece housing D, a diaphragm plate 39 being secured between said lower section and the upper section 40 of said housing and having the free end of a depending valve stem 41 secured centrally thereof, the lower end of the stem carrying a valve 42 adapted to open and close a valve seat 43 formed in the adjacent extremity of said reduced end 37. As shown in Fig. 1,

the upper section 40 of the housing is also provided with a reduced portion 44, which is interiorly threaded to receive a suitable stem 45, the lower portion of which is hollowed out to accommodate a helical spring 46, which as will be understood bears against the stem at one end and at the other against the adjacent face of the diaphragm. By turning the stem one way or the other, the tension of the spring is increased or decreased as the case may be with a corresponding effect on the diaphragm so that more or less pressure will be required to effect the seating of the valve 42.

Communicating with the interior of the reduced portion 37 of the housing is a pipe 47 having a check valve 48 and a shut-off valve 49, and which extends horizontally through the wall of the tank A, thence upwardly in the arc of a circle, and terminates in an open end directly above the wheel motor C into the pockets of which it is designed to deliver for the purpose of driving the same and its attached parts for feeding carbide into the water.

Extending downwardly from the lower end of the T-coupling 34, to which it is connected, is a pipe 50 having a shut-off valve 51 opening into one of the branches 30 of a three-way coupling 52, another of said branches being connected with a drain cock 53, and the third branch being connected to an end of a horizontal pipe 54 extending through the wall of the tank and a suitable bushing 55 secured thereto. The other end of the pipe 54 communicates with the interior of the auxiliary pressure tank B at or adjacent the bottom thereof as shown.

Secured about the outer wall of the main pressure tank A, as by means of a band 56, is a comparatively small chamber or vessel E having in its upper portion a filling funnel 57 provided with a valve 58. The vessel is also provided with a suitable faucet 59 for regulating the level of the liquid, such as water, within the vessel.

A pipe 60 having a valve 61 is connected at one extremity to the wall of the tank A adjacent its upper end from whence it passes through the upper portion of the vessel E and terminates at its other open extremity at a point slightly spaced above the bottom of the vessel. A short service outlet pipe 62 extends from the upper portion of the vessel and permits the attachment thereto of a flexible or other tubing (not shown) leading to a torch or torches or other desired point.

In Figs. 4 and 5 are shown details of construction of the wheel motor C. This motor comprises a hub 63 through which the shaft 27 passes and from which spokes 64 radiate to a rim F formed of a pair of annular spaced flat side rings 65 secured together by a plurality of especially positioned transverse bolts, those 66, but the

inner periphery of the flanges being arranged in spaced pairs, each bolt of a pair being distanced slightly from the other; while those, 67, adjacent the outer periphery of the rings are individually spaced 70 thereabout in the manner shown in Fig. 4. A long metal plate, as of copper, 68, which is of sufficient width to completely span the space between the rings 65, is entwined about the bolts 66 and 67 as illustrated in 75 the figure last mentioned to form a series of pockets 69 extending entirely around the wheel, it of course being understood that the meeting ends of the plate are secured together in any desired way, and that when 80 motive power is brought to bear upon the wheel, it travels in the direction of the arrow (see Fig. 4).

A substantially U-shape member having a rigid arm 70 and a pivoted arm 71 is secured about one of the rods 16 by means of a split clamp 72. The rigid arm is provided with a threaded aperture through which an adjusting rod 73 threaded at 74 works, one end of the rod passing through 90 the wall of the tank and a bushing 75 (see Fig. 3) and the other end abutting the adjacent face of the pivoted arm 71. A spring 76 is secured to the respective free ends of the arms 70 and 71 and tends to hold the 95 latter arm in contact with the end of the rod 73. A boss 88 formed on the arm 71 affords means for securing thereto one extremity of a finger 78 attached at its other extremity to an inclined scraper blade or 100 plow 79, the lower edge of which overlies the receiving surface of the disk 19 in close proximity thereto, so that during the rotation of the disk, material as carbide, deposited thereon will be scraped from the 105 disk by the blade and fall into a body of water in the tank A. By turning the rod 73, it will be seen that the angularity of the blade 79 may be adjusted across the face of the disk for the purpose of depositing 110 more or less carbide into the water.

A funnel 80 having a shut-off valve 81 permits the filling of the tank A with water to the desired level, a suitable faucet 82 placed in the wall of the tank governing 115 the height of such level. The hopper 11 is then filled with carbide which feeds through the lower delivery end thereof onto the disk 19. The hand wheel 80 is next turned, which, as will be understood from the foregoing description, imparts rotary motion to the disk and some of the carbide thereon is scraped therefrom by the blade 79 and delivered into the water resulting in the generation of gas which fills the upper portion 120 of the tank, a pressure gage 82' affording means for determining the pressures of gas at all times within the tank. The valves 32, 51 and 49 are then opened and the water under pressure is forced into the auxiliary 130

tank B compressing the air therein until the pressure, say for example 17 pounds, is equalized in both tanks. The manual turning of the wheel 30 may be stopped and the 5 valve 61 opened so that the gas in the upper portion of tank A flows through pipe 60 into the lower portion of the vessel E, filtering through a body of water previously placed in the vessel and passes out through 10 the pipe 62 and a tubing attached thereto to a suitable source.

As soon as the pressure in tank A falls below that in tank B, the water in the latter tank is forced therefrom outwardly through 15 pipe 54 and up through pipe 52 past the open valve 42 into the lower portion of the housing from whence it passes via pipe 47 and delivers through the open upper end thereof into a pocket 69 of the wheel motor 20 C, filling such pocket and overflowing into the next adjacent lower pocket, the side rings 65 projecting sufficiently above the pockets to guide the overflow of water from the higher to the lower pocket or pockets. 25 The check valves 33 and 48 respectively, prevent the return of the water into the tank A and housing.

When a number of the pockets on one side of the wheel having been thus filled with 30 water, the increased weight causes the wheel and its shaft 27 to rotate which again turns the disk 19 so that further carbid is delivered into the water of tank A, resulting in the generation of more gas and the operation 35 outlined above is repeated.

A pressure gage 85 is used for registering the pressure at all times within the housing, to which it is attached: while the stem 45 and spring 46 comprise means which may 40 be regulated to determine the degree of pressure allowed to pass through the housing for the purpose of actuating the wheel motor. Should the pressure within the housing register a greater degree than is desired, it will 45 be understood that the stem 45 is turned in the proper direction to reduce the tension of the spring 46 so that the excess pressure will act on the diaphragm to close the valve 42 and thus shut off the pressure. As soon 50 as the pressure against the diaphragm falls below the predetermined degree, the valve 42 opens and permits the inflow of further pressure.

A cylinder 86, having an exhaust 87 to 55 atmosphere, is threaded into the closure member 14 of the tank A with which it communicates at its lower end and is provided with an offset upwardly extending arm 88' to the free end of which is pivotally 60 attached an end of a substantially horizontal rod 89 carrying a weight 90 adjustable therewith. At its free end, the rod 89 is pivotally connected to an end of a depending rod 91 passing through a guide bracket 92 fastened upon the wall of tank A. A dog 93

is pivoted between ears 94 on the wall of the tank and is normally supported in unengaging position by contact with the rod 91 as shown. Reciprocably mounted within the cylinder 86 is a piston 95 having a stem 70 96 extending upwardly through the top of the cylinder and connected with the horizontal rod 89. Should for any reason the pressure within the tank A become excessive, carbid is fed too rapidly as by hand operated feed, such excess pressure will cause the piston 95 to rise within its cylinder which will withdraw the rod 91 from engagement with the dog 93 and permit it to enter one of the notches 97 formed in the 80 periphery of the hand heel 30, thus stopping further rotation of shaft 27 and disk 19 and delivery of carbid into the water. The exhaust 87 permits the escape of excess pressure to atmosphere when the piston 95 has 85 been raised a sufficient extent in the cylinder. The block or weight 90 may be adjusted longitudinally of the rod 89 to determine the movement of operation of the auxiliary safety mechanism just described. 90

In order to facilitate access to the working parts within the tank, the latter is provided at any desired point in its wall with a removable closure member 103 adapted to be held in place fluid tight by means of bolts 95 104 or other securing means.

At its lower end, the tank A is provided with a trough shaped insert 98 across the lower portion of which extends a spiral agitator 99 journaled at one end in a stuffing box 100 and extended therebeyond to receive a crank handle 101. At its other end, the spiral is reduced in diameter and passes through the wall of the tank, a valved nipple 102 being secured to the tank at this point 105 and forming a bearing for the spiral. When desired, the spiral may be turned so as to agitate the carbid residue within the bottom of the tank and due to the particular construction of the agitating means employed, 110 I avoid the difficulty heretofore encountered in slushing the generator.

In accordance with the patent statutes, I have described the principles of operation of my invention, together with the apparatus which I now consider to represent the best embodiment thereof, but I desire to have it understood that the construction shown is only illustrative, and that the invention can be carried out by other means 115 120 and applied to uses other than those above set forth within the scope of the following claims.

Having described my invention, what I claim as new and desire to protect by Letters Patent is:—

1. A gas generator comprising a main tank having a body of water therein, a carbid chamber disposed wholly within said tank, an auxiliary tank associated with said 130

main tank, means for feeding and storing water under pressure from said main tank in said auxiliary tank, and rotatable means actuated by the release of said water under pressure for assisting in the delivery of carbide from said carbide chamber into said body of water.

2. A gas generator comprising a main tank having a body of water therein, a carbide chamber within said tank, a rotatable member for receiving carbide from said chamber and adapted when rotated to deliver a portion of its load into said water, a motor operatively connected with said member to 10 rotate the same, an auxiliary tank, means for storing water under pressure from said main tank in said auxiliary tank, and means for delivering the water under pressure from said auxiliary tank to actuate said motor 15 and rotate said member.

3. A gas generator comprising a main tank having a body of water therein, a carbide chamber within said tank, a rotatable member for receiving carbide from said chamber and adapted when rotated to deliver a portion of its load into said water, a motor operatively connected with said member to 20 rotate the same, an auxiliary tank, means for storing water under pressure from said main tank in said auxiliary tank, and means for delivering the water under pressure from said auxiliary tank to actuate said motor 25 and rotate said member.

4. A gas generator comprising a main tank having a body of water therein, a carbide chamber within said tank, a rotatable disk for receiving carbide from said chamber, means for removing carbide from said disk during rotation, and delivering it into 30 said body of water, a motor operatively connected with said disk to rotate the same, an auxiliary tank, means for storing water under pressure from said main tank in said auxiliary tank, and means for delivering the water under pressure from 35 said auxiliary tank to actuate said motor and rotate said member.

5. A gas generator comprising a main

tank having a body of water therein, a carbide chamber within said tank, a rotatable 50 disk for receiving carbide from said chamber, means extending at an inclination from said disk for scraping carbide therefrom during rotation and delivering it into said body of water, a motor operatively connected with 55 said disk to rotate the same; an auxiliary tank, means for storing water under pressure from said main tank in said auxiliary tank, and means for delivering the water under pressure from said auxiliary tank to 60 actuate said motor and rotate said member.

6. A gas generator comprising a main tank having a body of water therein, a carbide chamber within said tank, a rotatable disk for receiving carbide from said chamber, means extending at an inclination from and angularly across said disk for scraping carbide therefrom during rotation and delivering it into said body of water, a motor operatively connected with said disk to rotate 70 the same, an auxiliary tank, means for storing water under pressure from said main tank in said auxiliary tank, and means for delivering the water under pressure from said auxiliary tank to actuate said motor 75 and rotate said member.

7. A gas generator comprising a main tank having a body of water therein, a carbide chamber within said tank, a rotatable disk for receiving carbide from said chamber, 80 a blade extending at an inclination from and angularly across said disk for scraping carbide therefrom during rotation and delivering it into said body of water, means for adjusting the angularity of said blade, a motor operatively connected with said disk to rotate the same, an auxiliary tank, means for storing water under pressure from said main tank in said auxiliary tank, and means for delivering the water under pressure 85 from said auxiliary tank to actuate said motor and rotate said member.

In testimony whereof, I have signed my name to this specification.

DAVID F. GEIGER.
